(57) **CLAIM**

The ornamental design for 3D printer as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front perspective view of a 3D printer showing the new design;

FIG. 1.2 is a front view thereof;

FIG. 1.3 is a back view thereof;

FIG. 1.4 is a right side view thereof;

FIG. 1.5 is a left side view thereof; and

FIG. 1.6 is a top view thereof.

The figures presented herein are rendered in color to facilitate understanding of the design and to enhance visual contrast. However, color is not claimed as a feature of the ornamental design.
